UNDERGARMENT

William P. McCarthy, Chicago, Ill., assignor to
Herman M. McDonald, Evanston, Ill.

Application June 21, 1939, Serial No. 280,297

7 Claims. (Cl. 2—234)

This invention relates in general to undergarments and more particularly to an undergarment for men having a double support due to the crossing of straps supporting the pouch with straps to the crotch, both extending to the waist band.

A principal object of the invention is the provision of an undergarment having a horizontal fly opening which is supported by straps to prevent sagging.

Another important object of the invention is the provision of an undergarment for men which is much cooler than that heretofore in use and which is more comfortable, because the crotch and pouch portion of the garment is made with only one thickness and with a minimum overlapping of material.

Numerous other objects and advantages of the invention will be apparent as it is better understood from the following description, which, when taken in connection with the accompanying drawings, discloses a preferred embodiment thereof.

In the drawings,

Figure 1 is a front elevational view of an undergarment embodying the features of the invention, illustrating the preferred embodiment thereof;

Figure 2 is a front elevational view of the garment of Fig. 1 turned inside out;

Figure 3 is a front elevational view of a modified form of garment;

Figure 4 is a front elevational view of the garment of Fig. 3 turned inside out;

Figure 5 is a front elevational view of a further modified form of undergarment; and

Figure 6 is a front elevational view of the garment of Fig. 5 turned inside out.

Referring more particularly to Figs. 1 and 2, reference numeral 11 indicates in general an undergarment for men commonly known as the mid-length type, or as trunks. The garment 11 may be made from any suitable fabric, preferably a woven or knitted fabric, and is composed of a rear section 12 and a front section 13. The front and rear sections are joined together at the sides in the usual manner by sewing or stitching 14, and are preferably secured at the upper end at 15 to a relatively wide elastic band 16, which is adapted to fit snugly about the waist of the wearer. A reinforcing band 17 is sewed to the bottom of the leg extension 18 to provide a smooth edge therefor and to prevent the ends of the fabric from becoming unraveled.

The upper part of the front section 13 is cut away to form an opening 19, the lower part of which is somewhat V-shaped. The central part of a strap 21 is sewed to the lower V-shaped edge of the opening 19, and the ends of the strap 21 extend upwardly and outwardly across the front section 13 to the upper edge of the waist band 16, being secured thereto in any suitable manner. An insert 22 is shaped similarly to and 5 is slightly larger than the opening 19 and is adapted to extend downwardly from the waist band 16 to shortly below the V-shaped lower end of the opening 19. The sides of the insert 22 are sewed to the section 13 along the substantially vertical edges of the opening 19. A pair of straps 23 are then sewed along these edges to the insert 22 and extend downwardly from the waist band 16 to the crotch 24 of the garment 11. The lower edge 25 of the insert 20 22 is not sewed to the section 13 in order to provide a fly opening from the outside of the garment 11 to the inside thereof.

A substantially horizontal fly opening is thus formed in the front section 13 of the garment 20 11 which is supported by the straps 21 and 23 to prevent undesired sagging and gapping. The two sets of crossed straps 21 and 23 also act as a double support for the pouch portion of the garment. In addition, these features enable the 30 use of only a single thickness of material for the crotch and the pouch portion, with a minimum of overlapping at the fly, to provide an extremely cool and comfortable garment.

Figs. 3 and 4 illustrate a modification of the 35 garment shown in Figs. 1 and 2. Reference numeral 31 indicates the garment generally which comprises a front section 32 and a rear section 33. The front and rear sections are joined together at the sides by sewing or stitching 34, 40 and are sewed, as at 35, to a relatively wide elastic strip or band 36, which is adapted to fit snugly about the waist of the wearer. A reinforcing band 37 is sewed to the bottom of each leg extension 38 to prevent the edges of the leg 45 extensions from becoming unraveled.

The lower portion of the front section 32 is cut away to provide an opening 39 (Fig. 4) extending upwardly from the crotch of the garment. An insert 41 of substantially the same 50 shape but slightly larger than the opening 39 is sewed to the crotch at its lower edge and to the front section 32 along its side edges to cover the opening 39, this insert 41 extending a short distance above the upper horizontal edge 42 of the opening 39. The upper edge of the insert 55

41 is substantially V-shaped (Fig. 3), and is not connected to the front section 32. A strap 43 is sewed to this upper edge of the insert 41 and extends upwardly and outwardly across the front section 32 to the waist band 36. The end portions of the strap 43 are sewed to the front section 32 and to the waist band 36 to provide a support for the pouch portion formed by the insert 41 and also to reinforce the garment and prevent the same from becoming misshapen through use. A pair of straps 44 are also sewed to the front section 32 and the outer edges of the insert 41 along the edges of the opening 39, extending from the waist band 36 downwardly to the crotch 45 to provide a secondary supporting means and reinforcing means for the garment. A substantially horizontal fly opening is thus formed in the front portion of the garment 31, and the straps 43 and 44 function in the same manner as the straps 21 and 23 of the garment shown in Figs. 1 and 2.

Figures 5 and 6 illustrate a further modification of the invention in which reference numeral 51 indicates in general an undergarment comprising a front section 52 and a rear section 53. The sections 52 and 53 are joined at their sides at 54, and the upper end of these sections is secured at 55 to a relatively wide elastic waist band 56. The lower portion of the leg extensions 57 have a band 58 sewed thereon to prevent the ends of the material from becoming unraveled. The front section 52 has an opening 59 cut therein which is similar in size and shape to the opening 41 in the front section 32 of the modification of Figs. 3 and 4. An insert 61, substantially identical to the insert 41, is sewed along its outer edges to the front section 52, and is adapted to cover the opening 59 and extend a short distance above the horizontal edge 62 formed by the opening 59. The upper edge of the insert 61 is also cut substantially V-shaped, and a strap 63 is sewed thereto. The end portions of the strap 63 extend upwardly and outwardly across the front section 52 to the waist band 56 and are sewed thereto in any suitable manner. Extending downwardly from the strap 63 are a pair of straps 64 which are sewed along the substantially vertical marginal edges of the insert 61 to the latter and to the front section 52. The lower ends of the straps 64 terminate at the crotch 65 of the garment. A substantially horizontal fly opening is thus provided in the garment 51 which is supported by straps 63 and 64, the latter also supporting the pouch portion formed by the insert 61.

It is to be understood that, while the instant drawings disclose a mid-length type of undergarment, the embodiments of the invention disclosed therein are equally well adapted for use in ankle length, briefs, or other types of undergarments.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. An undergarment adapted to sheathe the lower part of a human body, comprising a crotch portion, a front section having an aperture formed therein above said crotch portion, an in-

sert similar in shape along its side edges and slightly larger than said aperture overlying the latter and secured along its side edges and the sides of said aperture to said front section and unattached thereto along one edge to provide a substantially horizontal fly opening therebetween, and a reinforcing strap-like member secured intermediate its ends to the edge of the outer portion of said fly opening, the ends of said member extending upwardly and outwardly across said front section and being secured thereto.

2. An undergarment adapted to sheathe the lower part of a human body, comprising a crotch portion, a front section having an aperture formed therein above said crotch portion, an insert similar in shape along its side edges and slightly larger than said aperture overlying the latter and secured along its side edges and the sides of said aperture to said front section, with one edge of said insert being unattached to the front section to provide a substantially horizontal fly opening between said front section and said insert, a reinforcing strap-like member secured intermediate its ends to the edge of the outer portion of said fly opening, the ends of said member extending upwardly and outwardly across said front section and being secured thereto, and separate strap-like members secured to said front section and extending from said crotch portion to the upper part of said garment and along the sides of said aperture, said latter members crossing said first member.

3. An undergarment adapted to sheathe the lower part of a human body, comprising a front section, a rear section, said front section having an opening formed in the upper part thereof, said opening having its lower edge substantially V-shaped, a strap secured to said front section which binds said V-shaped edge and extends upwardly and outwardly to the upper edge of said front section, an insert secured at its sides to said front section adapted to fit said opening and unattached to said front section along said V-shaped edge to provide a horizontal fly opening, and a pair of straps extending upwardly from the crotch of said garment along the sides of said opening and said insert.

4. An undergarment adapted to sheathe the lower part of a human body, comprising a front section and a rear section, said front section having an opening formed in the lower part thereof, an insert secured along its sides to said front section to cover said opening, said insert having its upper edge substantially V-shaped and unattached to said front section to provide a horizontal fly opening, and a strap secured to the upper edge of said insert and to said front section and extending upwardly and outwardly to the upper edge of the latter.

5. An undergarment adapted to sheathe the lower part of a human body, comprising a front section and a rear section, said front section having an opening formed in the lower part thereof, an insert secured along its sides to the sides of said front section to cover said opening, said insert having its upper edge substantially V-shaped and unattached to said front section to provide a horizontal fly opening, a strap secured to the upper edge of said insert and to said front section and extending upwardly and outwardly to the upper edge of the front section, and a pair of straps extending upwardly along the sides of said insert from the crotch of the garment to the upper edge of the front section.

6. An undergarment, comprising a body portion made up of a front and a rear section joined at the crotch and sides of the garment, a waist band secured to the top margins of said front and rear sections, said front section having an aperture formed therein above said crotch, an insert similar in shape along its side edges and slightly larger than said aperture overlying the same and secured along its side edges to said front section, with one edge of said insert being unattached to said front section to provide a substantially horizontal fly opening therebetween, and a strap secured intermediate its ends to the edge of the outer portion of said fly opening, the ends of said strap being secured to and extending upwardly and outwardly across said front section and being secured to said waist band at points spaced laterally from said fly opening.

7. An undergarment, comprising a body portion made up of a front and a rear section joined at the crotch and sides of the garment, a waist

band secured to the top margins of said front and rear sections, said front section having an aperture formed therein above said crotch, an insert similar in shape along its side edges and slightly larger than said aperture overlying the same and secured along its side edges to said front section, with one edge of said insert being unattached to said front section to provide a substantially horizontal fly opening therebetween, a strap secured intermediate its ends to the edge of the outer portion of said fly opening, the ends of said strap being secured to and extending upwardly and outwardly across said front section and being secured to said waist band at points spaced laterally from said fly opening, and separate straps secured to said front section, said insert and said waist band and extending along the side edges of said insert from the crotch to the waist band, each of said latter straps crossing said first strap intermediate its ends and being secured thereto.
